United States Patent Office.

ROBERT F. TOMPKINS, OF NEW YORK, N. Y.

Letters Patent No. 92,491, dated July 13, 1869.

IMPROVEMENT IN MACHINE FOR CUTTING BEAD-MITRES.

The Schedule referred to in these Letters Patent and making part of the same.

To all whom it may concern:

Be it known that I, ROBERT F. TOMPKINS, of the city, county, and State of New York, have invented a Machine for Cutting Bead-Mitres; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

To any one used to cutting mitres on the beadings formed on the edges of mouldings, stiles, &c., in carpentry, the usefulness of this invention will be apparent.

In mortising together the stiles, &c., of window-shutters, blinds, doors, &c., where a beading runs along the edges of the wood used for the purpose, it is necessary, in order to give a finished appearance to the work, that the beading should come together with a mitre; and to do this expeditiously and neatly not only requires a skilled workman, but considerable time. By the use of my invention, however, this work may be done accurately and expeditiously by one of little skill, or even by a boy.

In the accompanying drawings—

Figure 1 represents a front side view;

Figure 2, a rear side view of the same; and

Figure 3, a plan, or top of my invention.

Similar letters of reference indicate like parts in the several drawings.

A is the bed-plate, upon which the machine is properly secured.

This bed-plate may be constructed of wood or cast-iron. I prefer to make it of wood, as it is both cheaper and lighter.

B is an upright cast-iron frame, standing at right angles to the bed-plate A, to which it is secured by the plates *a a*, cast in one piece with the frame B, and let into the bed-plate A, flush with its upper surface.

The plates *a a* are firmly secured to the bed-plate A by the screws *b b*, with countersunk heads.

Sliding freely up and down on the rods or guides *c c*, is the cast-iron block C, to which is bolted, or otherwise attached, the knife, or cutter D, by the tongue *e*.

This knife, or cutter D may be made of cast-steel or of wrought-iron, with steel cutting-edges.

In the shape and construction of this knife, or cutter, lies the chief merit of my invention.

It will be observed that this knife, or cutter has three distinct cutting-edges combined in one, viz, the projecting, or front edge *f*, which is parallel with the upper surface of the bed-plate A, and the cutting-edges *g g*,

formed at angles of forty-five degrees with the front edge *f*.

By reason of the peculiar shape of the knife, or cutter D, it will be observed that when a strip of moulding, or wood having a bead along its edge, is placed under the knife or cutter, with the beaded edge pressed closely against the fences *h h*, and the knife or cutter D is forced through the wood by the lever K, the edge *f* will cut the moulding or strip in a direction parallel with its length, while the edge *g* will, at the same time, neatly cut the beading on the edge of the strip to an angle of forty-five degrees, or mitre; and this operation may be repeated as often as may be required, depending upon the length of mortise, or otherwise, as the workman may see fit.

If, at any time, the knife or cutter D requires sharpening, it may be readily detached from the machine by simply loosening the set-screw *i*, and then sharpening it the same as any other tool or iron would be sharpened.

The knife or cutter D is confined to its position by sliding between the projecting edges of the guide-plates *l l*, and the frame B.

The play of the knife between these guide-plates and frame may be regulated by the set-screws *w w*.

As the size of beadings vary, I accommodate the action of the machine to the various sizes by means of the fences *h h*, which are projected to the front, thus exposing less cutting-surface of the knife where the beading is small, and *vice versa*.

The ends of these fences next the knife or cutter are so constructed as to move always parallel with the edges *g g*.

This is accomplished by means of the angular guides or slides *m m*, and set-screws *n n*.

The plates *a a*, besides securing the frame B to the bed-plate A, answer the double purpose of keeping the bed-plate from wearing away at the cutting-point, and thus keeping the surface of the bed-plate exactly at right angles to the edges of the knife or cutter D.

As the moulding or strip may, in some instances, be thinner than at others, I regulate the throw of the knife by the screw *p*, which, when screwed inward, shortens the slot *r*, and thus leaves less play for the pin *s*, as is clearly shown in fig. 2.

The bed-plate A has a depression, *t*, corresponding in shape and size with the knife or cutter D, into which the knife or cutter is forced when passing through the moulding and bead, thus insuring a clean cut, without burr.

The lower ends of the rods or guides *c c* are fitted into the cross-bar *j*, which is cast into the frame, and the upper ends pass through the upper part of the frame, where they are secured by the nuts *o o*.

I am aware of the patent granted to G. W. La Baw, dated 29th May, 1855, and I hereby disclaim his invention.

Having thus fully described my invention, What I claim as new, and desire to secure by Letters Patent, is—

The knife or cutter D, adjustable fences *h h*, with the angular guides or slides *m m*, frame B, guide-

plates *l l*, when all are constructed and arranged to operate for the purposes hereinbefore set forth and described.

ROBERT F. TOMPKINS.
